(Cl. D47—7)

To all whom it may concern:

Be it known that I, Abrasha Wilcher, a citizen of the United States, residing at 103 Bay Street, Manchester, New Hampshire, have invented a new, original, and ornamental Design for a Lady's Stocking, of which the following is a specification, reference being had to the accompanying drawing, forming a part thereof in which:

Figure 1 shows a perspective view of my new design for a lady's stocking as viewed from the side; and,

Figure 2 is an enlarged fragmentary rear view of the stocking shown in Figure 1.

The other side of the stocking is the same as the side shown and the heavier shaded area indicates closer weave than other parts of the stocking of the same shades.

I claim:

The ornamental design for a lady's stocking, as shown and described.

ABRASHA WILCHER.
